(57) **CLAIM**

The ornamental design for a microphone support, as shown and described.

DESCRIPTION

FIG. 1 is a first perspective view of a microphone support, showing the new design;

FIG. 2 is a second perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is right side view thereof; and,

FIG. 9 is a front view thereof, in an alternate position.

Evenly broken lines in FIGS. 1–8 depict portions of the microphone support which form no part of the claimed design. Evenly broken lines in FIG. 9 depict environmental structures which form no part of the claimed design.

1 Claim, 9 Drawing Sheets
